UNITED STATES PATENT OFFICE.

GLEASON W. ROMER, OF LAKE HELEN, FLORIDA.

DEVELOPING APPLIANCE FOR PHOTOGRAPHIC PRINTS.

1,299,229.

Specification of Letters Patent.

Patented Apr. 1, 1919.

Application filed June 15, 1918. Serial No. 240,183.

To all whom it may concern:

Be it known that I, GLEASON W. ROMER, a citizen of the United States, residing at Lake Helen, in the county of Volusia and State of Florida, have invented certain new and useful Improvements in Developing Appliances for Photographic Prints, of which the following is a specification.

My invention relates to the art of photography, and is especially designed for use during the process of developing photographic prints.

The prime object of the invention is to provide a simple, durable, economical and efficient appliance whereby the prints may be handled, held or carried and manipulated during the various steps attending development, said appliance being formed from a single piece of any suitable material not affected by the chemical agents employed.

A further object of the invention is to so construct my novel appliance that the film or print may be readily manipulated, thus preserving the hands and fingers of the operator from contact with the acids and poisonous development solution, thereby preventing stained fingers and nails, the eating of the fingers and all other injurious effects of the hands usually produced by the said solution, and the operator's hands are kept clean, thereby enabling him to produce better work, since the paper can be handled, printed and numbered, prints placed in the developer and handled throughout all of the solutions without causing the operator to stop to wash and dry his hands from time to time, and it also eliminates the use of rubber gloves, finger tips and all anti-stain preparations heretofore employed.

Another object of this invention is to provide a device of such peculiar shape or configuration that the operator can handle as many prints, and in the same time, as the operator would be able to handle with the natural hand, since the lateral curve of the device at the clamping end portion thereof is designed to give it the natural position assumed by the human hand during the process of developing the prints, and the downward curve of the appliance toward its outer end portion enables the operator's hand to be elevated above and out of the developing solution, and at the same time permits the clamping end of the device to be placed flat on the bottom of the developing tray in order to engage and lift the print, and it also en-

ables the device to be balanced or supported on the edge of the tray when not in use.

The foregoing and such other objects as may appear from the ensuing description are attained by the construction and arrangement of the parts hereinafter more fully described, illustrated in the accompanying drawings, and particularly pointed out in the claims appended hereto, it being understood that slight changes in the precise form and construction may be resorted to without departing from the spirit or sacrificing any of the advantages of the invention.

In the accompanying drawings which form a part of the specification it will be seen that:—

Figure 1, is a perspective view of the novel appliance embodying my invention, showing it in the hand of the operator with a photographic print clamped and supported thereby.

Fig. 2, is a side view of the appliance showing it held in the hand in its open or normal position.

Fig. 3, is a similar view showing the appliance in its closed or clamping position.

Fig. 4, is a plan view of the appliance.

Fig. 5, is a transverse section, taken on the line 5—5, Fig. 4, and

Fig. 6, is a reduced plan view of a blank from which the appliance is formed.

Similar numerals of reference are employed to designate corresponding parts throughout the several figures of the drawings.

In carrying out my invention and which illustrates the preferred construction, the numeral 1 indicates the lower member of my novel appliance, and 2 designates the upper member, said members being formed from a single piece of suitable or desirable material and joined at the central or bent portion 3. The lower member is provided at its outer end portion with an enlarged flat rounded clamping portion 4, having a beveled portion 5 at its outer edge, and near its outer edge is formed a plurality of depressions 6 in its lower and outer surface, serving as suction depressions to elevate or lift the print slightly when it becomes unduly flattened against the bottom of the developing tray or any other support, so that the portion 4 may be readily slipped thereunder, while the upper member 2 is provided at its outer end portion with a smaller or reduced rounded clamping portion 7, as shown in Fig. 4 of the drawings,

2
whereby when the upper and lower members are pressed into the closed position by the thumb and fingers of the operator's hand, as clearly shown in Figs. 1 and 3, the print will be clamped between the portions 4 and 7 of the appliance, and thereby handled and suitably manipulated by the operator during the entire developing process, without the hand or fingers coming into contact with the 10 poisonous developing solution, and as soon as the pressure of the thumb and fingers are entirely released the print will fall or be delivered from the appliance by the resiliency of the members 1 and 2, and said members will 15 be caused to automatically assume their open or normal unclamped position such as shown in Fig. 2.

It will be readily perceived that the downwardly curved outer portion of the appliance readily permits the dipping of the print in the solution, and the easy removal of it from the shallow developing trays, without the hand or fingers coming into contact with the said solution, while the laterally formed curve at the clamping end portion of the members causes the device to assume the natural position of the human hand during the print developing process.

It will be understood that the depressions 30 formed in the under surface of the lower clamping portion may be dispensed with if desired, since the beveled or sharp outer edge formed on the portion 4 can be easily slipped beneath the print in almost all conditions, in 35 order to elevate the print to a clamping position, and that the appliance may be formed of any suitable material such as sheet brass plated with nickel; sheet steel, celluloid, or other desirable material possessing the necessary resiliency when the device is formed 40 into the shape or configuration such as illustrated in the accompanying drawings.

The clamping portion 4 is enlarged so as to form a greater area of bearing surface for 45 the print to rest upon when clamped by the appliance, thereby materially lessening the possibility of the print being broken, torn or otherwise defaced during the handling of the print while in a wet or moist condition as 50 the process of development is completed.

Having thus described my invention, what I claim and desire to secure by Letters Patent is:

1. An appliance of the character described

composed of a single piece of material bent 55 upon itself to form an upper and a lower resilient arm, clamping members formed upon the terminals of the arms, one clamping member being of greater length and width than the other member, the body portion of each arm being provided with a downwardly curved portion, and each arm being curved laterally with respect to the body portion near its terminal end portion for the purposes described.

2. An appliance of the character described consisting of a single piece of material bent upon itself to form an upper and a lower resilient arm, a clamping member formed upon the terminal of each arm, one clamping 70 member being of greater length and diameter than the other member, the body portion of each arm being provided with a downwardly bent portion, and each arm being bent laterally with respect to the body portion near its terminal end portion for the purposes described.

3. An appliance of the character described comprising a single piece of material bent upon itself to form two arms, clamping 80 members formed upon the terminals of said arms, the lower one of said members having an enlarged clamping end portion extending at all points beyond the reduced clamping end portion of the upper member, and 85 both arms having a downward curved body portion and a lateral curved portion near its terminal end for the purposes described.

4. An appliance of the character described comprising a single piece of material bent 90 upon itself to form an upper and a lower resilient clamping member, each member formed with a downward curve and a lateral curve near its outer end portion, the lower member being provided with a beveled outer 95 edge, and a plurality of depressions near its outer edge for the purposes described.

5. An appliance of the character described comprising a single piece of material formed into two resilient clamping members, each member formed with a lateral curve near its outer end portion, the end portion of one member being larger than the other and provided with a beveled outer edge, and a plurality of depressions formed therein near 100 its outer end for the purposes set forth.

GLEASON W. ROMER.
